UNITED STATES PATENT OFFICE.

RALPH M. LICKLEY, OF EAST CLEVELAND, OHIO, ASSIGNOR, BY MESNE ASSIGNMENTS, TO THE TALMAGE MANUFACTURING COMPANY, OF CLEVELAND, OHIO, A CORPORATION OF OHIO.

SMOKE-ABATING SYSTEM FOR LOCOMOTIVES.

1,275,056.

Specification of Letters Patent. Patented Aug. 6, 1918.

Application filed August 10, 1915. Serial No. 44,688.

To all whom it may concern:

Be it known that I, RALPH M. LICKLEY, a citizen of the United States, residing at East Cleveland, in the county of Cuyahoga and State of Ohio, have invented a certain new and useful Improvement in Smoke-Abating Systems for Locomotives, of which the following is a full, clear, and exact description, reference being had to the accompanying drawings.

The ultimate object of this invention is to increase the efficiency in production of steam in a locomotive, and at the same time, abate the smoke. My invention accomplishes this by injecting into the fire box superheated steam and air which consumes carbon rising from the fire, thus increasing the heat produced, protecting the flues from sooty deposits, and minimizing the smoke discharged. I have found that superheated steam approximates heated air much more nearly than does saturated steam, and, by using superheated steam through a nozzle as a means of injecting adjacent air, I cause an intermingling of the superheated steam and air, producing a hot mixture devoid of moisture and ready for instant combination with the products of combustion from the fire bed.

As superheated steam is only available in a modern locomotive while the same is running, I provide a device for automatically shifting from superheated to saturated steam whenever the supply of superheated steam ceases by reason of the closing of the throttle. This enables the same nozzles to discharge saturated steam and air into the fire box when the locomotive is drifting or stationary, to abate the smoke as far as it may be accomplished by saturated steam injection. As soon as the superheated steam becomes available in the running of the locomotive, my device automatically connects the discharge with the supply of superheated steam, thus giving the maximum of efficiency and the minimum of smoke in the fire box action.

The drawings illustrate an equipment for carrying out my system of smoke abatement. Figure 1 is a plan of such equipment and Fig. 2 is a side elevation thereof. In each of these views the locomotive is indicated by broken lines, being imposed over the added equipment to illustrate the position of such equipment on the locomotive. Fig. 3 is a

vertical section through the fire box; Fig. 4 is a vertical section on a larger scale through the automatic valve for causing the change from superheated to saturated steam, and vice versa.

Describing the particular embodiment shown in the drawings, A, in Fig. 2, indicates the dry pipe of a locomotive leading from the steam dome and controlled by a throttle valve B operated by the usual throttle lever C. The dry pipe divides into a series of smaller pipes which loop back and forth within tubes in the upper portion of the boiler, these loops constituting the superheater D. From the superheater, the various tubes join in a common discharge pipe E which leads to the steam chest. F indicates the grate of the fire box; G a suitable brick arch above the doorway; H a suitable brick baffle above the fire box and extending diagonally upward in front of the tubes, these bricks being shown as supported by water tubes I. So much of the construction represents simply a modern, superheating locomotive.

In the embodiment of my invention shown in the drawings, I provide a series of thimbles 10 extending through the back of the locomotive a short distance above the fire door K, and a series of thimbles 11 extending inwardly from the sides of the locomotive below the tubes I. Located centrally in these thimbles are nozzles 12 and 13 leading from a common pipe 15 which extends across the back and forwardly onto the sides of the fire box. The nozzles are shown as connected with the pipe 15 by T's or elbows 14. This pipe is fed by an admission pipe 17 which is adapted to be connected with a supply of superheated steam or saturated steam, as the case may be, and as will now be described.

20, in each of the figures, indicates the casing of an automatic valve. This casing has three passageways to or from it and a piston for controlling them. Thus, 21 at the upper end of the casing is a passageway connected by a pipe 22 to the supply of saturated steam, the connection being preferably through the hand valve 23 to the usual steam turret 24 in the cab. 25 is a passageway in the valve casing 20 connected by a pipe 26 with the superheater— as shown connected with the discharge pipe E leading from the superheating loops to 110

the steam chest. 28 is the third passage which connects with the pipe 17 leading to the pipe 15, which carries the discharge nozzles. It will be seen from an inspection of Fig. 4 that the passageways 25 and 28 connect with a large chamber 30 in the casing 20, while the passageway 21 leads to a comparatively small chamber 31. These chambers are cylinders occupied by a piston having the large portion 32 and the small portion 33. Leading from the chamber 31 to the passageway 28 is a passageway 35. The piston extension 33, it will be seen, in the upper position of the piston, closes the port 36 to the passageway 35 while leaving open the ports 37 from the superheating passageway 35 and the port 38 to the discharge passageway 28.

In the operation of the device illustrated, the hand valve 23 is maintained open and saturated steam constantly passes via the pipe 22 to the chamber 31 and acts on the upper end of the small piston extension 33. When superheated steam is available it passes via the passageway 25 to the chamber 30 and, acting on the much larger area of the piston portion 32, maintains the piston elevated and thus the ports 37 and 38 opened, and the port 36 closed. Accordingly, the saturated steam is shut off while superheated steam passes uninterruptedly from the pipe 26 through the valve casing to the nozzles. Whenever the supply of superheated steam ceases to be available, as takes place when the throttle is closed, the pressure drops in the chamber 30 and the saturated steam pressure in the chamber 31 shoves the piston downwardly, thus closing the port 38 and opening the port 36. Thereupon saturated steam passes via the passageway 35 to the nozzles and continues to discharge into the fire box until the throttle is again opened. As soon as the throttle is opened, superheated steam enters through the lower portion of the port 37 sufficiently to raise the piston, and this entirely uncovers the ports 37 and 38 and closes the port 36, leaving the nozzles supplied by superheated steam.

The various pipes described are of comparatively small bore, so that the amount of steam, either superheated or saturated, which is discharged into the fire box is comparatively small. The loss from this source is much more than counterbalanced by the increased combustion in the fire box. In addition to this there is the more efficient steaming of the boiler, due to the flues being kept clean, while the very desirable result of preventing the discharge of smoke is accomplished. By using superheated steam in place of saturated, I am able to not only

inject a hotter mixture of combustible gases, but one without moisture and in a more ready condition to combine with the products of combustion; while, whenever the desirable superheated steam is not available, I utilize the next best pressure fluid, namely; saturated steam.

Having thus described my invention, what I claim is:

1. The combination in a locomotive of a fire box, fire tubes communicating therewith, a boiler, a steam chest, a dry pipe connecting the boiler with the steam chest, a portion of said dry pipe consisting of a set of pipes located within the fire tubes and constituting a superheater, nozzles discharging into the fire box, a conduit leading to the nozzles, a conduit leading from the supply of saturated steam, a conduit leading from the supply of superheated steam, a valve casing communicating with said three conduits, and a movable valve member in said casing adapted to connect the nozzle conduit with either the superheated steam conduit or the saturated steam conduit.

2. The combination with a locomotive having a boiler, a throttle, a steam chest, a conduit from the boiler to the steam chest controlled by the throttle, there being a superheater included in a part of such conduit, of nozzles discharging into the fire box, a conduit for superheated steam leading from the superheater, a conduit leading from the supply of saturated steam, and means for connecting either of the two conduits last mentioned with the nozzles, said means including a differential piston valve having its larger area subjected to the action of the superheated steam.

3. The combination in a locomotive of a fire box, a boiler, a steam chest, a dry pipe connecting the boiler with the steam chest, a portion of said dry pipe being arranged to superheat driving steam, a throttle for controlling the admission of saturated steam to the dry pipe, nozzles discharging into the fire box of the locomotive, a conduit leading to said nozzles, a conduit for superheated steam leading from the superheater, a conduit for saturated steam leading from the boiler, and a valve adapted to connect either of the two conduits last mentioned with the conduit to the nozzles and having a piston normally held by the superheated steam pressure in position to maintain the superheater conduit open and the saturated conduit closed, but adapted to automatically open the saturated conduit when superheated steam is not available.

In testimony whereof, I hereunto affix my signature.

RALPH M. LICKLEY.
